UNITED STATES PATENT OFFICE.

WILLIAM S. HADAWAY, JR., OF NEW ROCHELLE, NEW YORK.

ELECTRIC HEATER.

1,154,111.

Specification of Letters Patent. Patented Sept. 21, 1915.

Application filed September 26, 1913. Serial No. 791,935.

To all whom it may concern:

Be it known that I, WILLIAM S. HADAWAY, Jr., a citizen of the United States, and a resident of New Rochelle, in the county of Westchester and State of New York, have invented 5 certain new and useful Improvements in Electric Heaters, of which the following is a specification, reference being had to the accompanying drawings, forming a part thereof.

10 My invention relates to electric heating devices, and particularly to such as are adapted to heat the ironing rolls of laundry machinery.

15 One object of my invention is to provide a heater that shall not only be simple and inexpensive to construct but that shall be readily applicable to laundry rolls and like devices of standard construction without involving either changes or additions in the 20 construction of the roll.

25 Another object is to provide an electric heater for a rotating object that shall effectively and efficiently impart heat thereto, but that shall be stationary and mechanically independent thereof, thereby avoiding all necessity for moving contacts and facilitating the control and adjustment of the heater.

30 Other objects of my invention will be set forth hereinafter, and in order that my invention may be thoroughly understood, I will describe the same in the following specification and then point out the novel features thereof in appended claims.

35 Referring to the drawings: Figure 1 is a front elevation on a relatively small scale of a laundry machine equipped with the heater of my invention. A longitudinal section of a laundry roll and a heater arranged 40 and constructed in accordance with my invention is shown in Fig. 2. Fig. 3 is an end elevation with the cap removed, of the heater shown in Fig. 2. A detail view of the heater element is shown in Fig. 4, together with a plan view of one of its supporting clamps or fasteners. A perspective view of one of the fasteners with its coöperating parts separated is shown in Fig. 5. Figs. 6 and 7 are diagrammatic views illustrating the circuit connections which may be 45 established between the heater units which form a part of the heater of my invention.

Corresponding parts are designated by the same reference characters in all the figures. 50 10 represents a hollow cylindrical laundry

roll or similar device which constitutes a part of a laundry machine 12 in which it is rotatably supported. The roll extends outwardly from the head of the machine and is only supported at one end in accordance 60 with the usual practice. The roll is arranged to coöperate with a rotatable guide roll (not shown) and the machine is so well known and understood that no explanation of its 65 operation is necessary.

Electric energy has hitherto been extensively used for heating laundry rolls but the heaters which have been employed have constituted an attachment to, or a part of, the roll structure and have been rotatable with 70 it. Heaters of this kind are arranged and intended to transfer the generated heat to the roll by conduction. Furthermore, they require slip rings or other moving contacts and therefore necessitate material changes 75 and additions to be made to the roll before they are operative. As usually constructed, 80 they have a relatively great inertia so that a comparatively long time is required to bring the roll up to the proper temperature. According to my present invention I provide 85 a heater which operates on an entirely different principle and which efficiently and rapidly imparts heat to the roll without either rotating with the roll or being in engagement with it at any point. The heater comprises a perforated sheet metal cylinder 20, a plurality of strips of sheet metal resistance ribbon 30 mounted thereon, a supporting ring 40 and a suspension bracket 90. The bracket may be of any suitable structure 95 and for example may comprise a substantially vertical pipe section 51 extending upwardly from a pipe flange 52 which is secured to the floor or other suitable base 53, and an overhanging section 54 connected to the upright 51 by suitable pipe joints 55.

The hollow cylinder 20 which forms a part 100 of the heater is fitted onto a cylindrical projection 41 of the supporting ring 40, and is secured in position by screws or bolts 42. The supporting ring comprises two parts which are secured together by screws arranged in three groups of two screws 43 and 43^a each. One of the parts 44 has a tapped sleeve projection 45 which is adapted to engage the screw-threaded lower end of the pipe section 54 of the bracket. The other member has the cylindrical projection 41 which is considerably smaller in diameter 105 110

than the section 44, and an annular body 46 in which are provided a series of apertures 47. The screw 43 of each group extends through a lug 49 of the member 44 and into 5 a tapped hole in a lug 49^a of the other ring member. The screw 43^a however extends through a tapped hole in the lug 49 and presses against the lug 49^a so as to tend to separate the members of the ring at the 10 point of contact. It is obvious that by manipulating the screws 43—43^a of the several groups, the cylinder may be readily centered in the roll. A terminal member 60 extends loosely through each of the apertures 15 47 and is secured to the annular body 46, being at the same time insulated from it by means of insulating bushings and washers in the usual manner. A screw 61 is secured in a tapped hole in the head of each of the 20 terminal members, and nuts 62 are provided on the shank of each terminal member which extends outwardly through the annular member 46 and is screw-threaded.

The sheet metal cylinder 20 is provided 25 with a plurality of apertures or perforations 21 arranged in longitudinal rows and adapted to receive hollow rivets 22 by means of which a clip 70 is held in position on its outer surface. Each of the clips 70, as 30 clearly shown in Figs. 4 and 5, consists of two L-shaped members 71—72 which are preferably stamped or punched from sheet metal. The member 72 has an offset lug 73 at one corner and an offset lug 74 spaced 35 from the lug 73 and centrally located. The member 71 has a hole 75 to receive the offset lug 74 and has an offset lug 76 at the opposite corner from the lug 73. The length of each branch of the L-shaped member 72 is 40 slightly less than the corresponding dimension of the member 71, the members being adapted to be nested together as shown in Figs. 2 and 4. Their bases are correspondingly perforated at 77 to permit one of the 45 hollow rivets 22 to extend through them.

The resistance element 30 preferably comprises a zigzag ribbon of relatively high resistance conducting material, a plurality of longitudinal strips of ribbon being employed as indicated by the diagrams of Figs. 50 6 and 7. One end of each strip of zigzag ribbon is clamped to one of the terminal members 60 as shown in Fig. 2, by means of one of the screws 61 and it is supported at 55 intervals by means of the clips 70, the ribbon being clamped between the members 71 and 72 of each clip and being prevented from slipping by the lugs 73—74—76.

At the outer end of the hollow cylinder 60 20 is secured a guard ring 23 which has a flange 24 of sufficient size to prevent the resistance element 30 from coming into engagement with the inside walls of the roll at any point. The guard ring 23 is particularly important since it prevents the

heater from becoming injured when it is being inserted in the roll 10. The roll is usually long relative to its diameter and the resistance ribbon and clips near its outer end would otherwise be liable to injury. 70

Attention is particularly directed to the fact that the heater *per se* is extremely simple and light in construction while at the same time it is mechanically independent and detached from the roll. It is furthermore stationary and consequently the connecting leads from the outer ends of the terminal members may be led through the pipe to any suitable point where simple knife blade or snap switches (not shown) 80 can be conveniently located for governing the circuit arrangement of the heater elements in order that the temperature of the roll may be regulated. The sheet metal disk 80 is arranged to close the end of the 85 ring 44, which constitutes a terminal box, and is held in place by screws 81. The disk 80 may be readily removed and the outer member 44 may be detached from the body 90 of the ring 40.

The sections of the heater element may be connected in any suitable manner depending upon the heat required and the voltage of the circuit from which energy is supplied. The arrangement of Fig. 6 is suitable for approximately double the voltage for which the arrangement of Fig. 7 is intended. Considering the heater as a whole, two-end terminals and one intermediate terminal are provided in each case in order 95 that the usual heat changes may be effected by utilizing one-half of the heater, the two sections in series or the two sections in multiple. It is unnecessary to distribute the sections of the heater element with uniformity or in any particular manner in a circumferential direction, so long as each section extends over the entire length, because of the fact that the roll to which the heat is imparted is not stationary but rotates. 100

As above indicated, it is usual to depend largely upon conduction for transferring the heat from the heater elements to the body. The heater of my invention however, is arranged and designed to operate at a high temperature and to transfer a large proportion of the heat generated in it to the roll which surrounds it by radiation and I have found that with an expenditure 115 of a relatively small quantity of electrical energy the roll may be very rapidly and economically heated. 120

Variations in size and arrangement of parts may be effected within the spirit and scope of my invention, and I desire that only such limitations be imposed as are indicated in the appended claims. 125

What I claim is:

1. An electric heater comprising a station- 130

ary support, a heat generator secured to and extending from said support, and means for adjusting the connection between the support and the heat generator, whereby the 5 inclination of the generator axis may be varied as desired.

2. An electric heater comprising a stationary support, a hollow cylindrical heat generator, and means for adjustably securing 10 the heat generator to the support only at one end, whereby the inclination of the generator axis may be varied as desired.

3. An electric heater comprising a stationary support, a ring having an annular 15 flange, a cylindrical heat generator secured at one end to said annular flange and extending outwardly therefrom, and means for adjustably securing the ring to the stationary support whereby the ring may be tilted 20 and inclination of the generator axis varied as desired.

4. An electric heater comprising a stationary support, a ring having a perforated 25 annular flange, a perforated sheet metal cylinder mounted on the ring and extending coaxially therewith in one direction therefrom, a resistance element supported by said metal cylinder, and an adjustable connection 30 between the ring and the support whereby the metal cylinder may be adjusted as to the inclination of its axis.

5. An electric heater comprising a stationary ring, a ring or collar adjustably connected thereto and having a perforated annular flange, a plurality of terminal members 35 extending axially of the ring through the perforations in said flange, a perforated sheet metal cylinder mounted on the flange and extending coaxially therewith in one 40 direction, and a resistance element supported and insulated from the outer surface of the metal cylinder, said adjustable connection between the rings being arranged to permit the adjustment of the cylinder with 45 respect to the inclination of its axis.

6. An electric heater comprising a stationary supporting ring, a second ring having an annular flange, a plurality of axial screws for securing the rings together, and axial 50 adjusting screws adjacent to the respective connecting screws and extending only through the supporting ring, a hollow cylindrical heat generator secured to the ring flange, the said connection between the rings 55 being arranged to permit the adjustment

of the cylindrical generator with respect to the inclination of its axis.

7. An electric heater comprising a perforated sheet metal support, hollow rivets extending through the perforations, a plurality of two-part clips secured to the support at the perforations by the hollow rivets and insulated therefrom, and a resistance element secured to the clips above the surface of the support. 60

8. An electric heater comprising a resistance element, a support, a plurality of two-part L-shaped sheet metal clips adapted to clamp the resistance element between them, the parts of each clip being secured together 70 and to the support by a single rivet.

9. An electric heater comprising a perforated sheet metal support, a plurality of two-part L-shaped sheet metal clips, a zig-zag resistance ribbon mounted edgewise relative to the surface of the support and clamped between the two parts of each clip, 75 a hollow rivet by which said parts are secured together and to the sheet metal member at a perforation therein.

10. An electric heater comprising a stationary ring having a perforated annular flange, a plurality of terminal members extending axially of the ring through the perforations in said flange, a perforated sheet 80 metal cylinder mounted on the ring and extending coaxially therewith in one direction, a plurality of two-part sheet metal clips secured to and insulated from the cylinder and extending outwardly from the surface 85 thereof, and a resistance element secured to a terminal member at one end and supported at intervals by said clips out of engagement with the surface of the cylinder.

11. In combination, a laundry roll rotatably supported near one end, a stationary electric heater supported near the opposite end of the roll and extending into the roll, and means for adjusting and determining the inclination of the heater relative to the 90 axis of the roll. 95

In testimony whereof, I have hereunto set my hand this 24th day of September, 1913, in the presence of two subscribing witnesses.
